UNITED STATES PATENT OFFICE

2,243,803

INSIDE CONTROL HOOD LATCH

Rowland Hill, Chicago, Ill., assignor to Chicago Forging & Manufacturing Company, Chicago, Ill., a corporation of Illinois

Original application February 17, 1939, Serial No. 256,965. Divided and this application August 4, 1939, Serial No. 288,264

9 Claims. (Cl. 292—340)

My invention relates to an improvement in latches and has for one purpose the provision of an improved latch for the closure of an automobile hood.

Another purpose is the provision of a latch assembly which shall be compact, easy to manufacture, and efficient in use.

Another purpose is the provision of means unitarily applicable to an automobile hood and hood closure having primary latching means, secondary safety latching means, and means for lifting the hood closure a predetermined distance in response to release of the primary latching means and prior to the release of the secondary safety latching means.

Another purpose is the provision of remote control latch means in which a latch, normally spring thrust into latching position, may move out of latching position to permit the keeper to drop into closed position, without affecting the remote control mechanism.

Other purposes will appear from time to time in the course of the specification and claims.

I illustrate my invention more or less diagrammatically in the accompanying drawings wherein:

Fig. 1 is a side elevation with parts in vertical longitudinal section;

Fig. 2 is a vertical longitudinal section on an enlarged scale illustrating part of the material shown in Fig. 1;

Fig. 3 is a section on the line 3—3 of Fig. 1;

Fig. 4 is a section on the line 4—4 of Fig. 3; and

Fig. 5 is a section on the line 5—5 of Fig. 4.

This is a division of my co-pending application Serial No. 256,965, filed February 17, 1939, now Letters Patent No. 2,209,886, dated July 30, 1940.

Like parts are indicated by like characters throughout the specification and drawings.

Referring to the drawings, and for example to Fig. 1 and following, I generally indicate an automobile hood and 2 a closure therefor, transversely and horizontally hinged at its rear end as at 3. It will be understood, however, that the hinge shown is diagrammatic and that any suitable mounting for the rear end of the closure 2 may be employed. 4 generally indicates the instrument panel of the vehicle.

Mounted on the hood 1 is a member which I may call a bottom plate, generally indicated at 6 and shown in some detail for example in Fig. 5. It is illustrated as having a transversely elongated aperture 7 surrounded by a downwardly

turned flange 8. The plate 6 may be mounted in any suitable fashion upon the hood 1. I illustrate for example flanges 9 at each side of the hood 1 to which the plate 6 may be secured by bolts 10 or by any other suitable securing means.

Any suitable adjusting slots may be provided on the plate 6, as shown for example at 11 in Fig. 5. Preferably the plate 6 is mounted for lateral adjustment, the slots 11 being laterally or transversely elongated, whereby the aperture 7 may be aligned with the latching means below described. 12 indicates any suitable securing lip provided with a downwardly turned flange 13 adapted to receive the secondary or safety latching member below described. The flange 13, it will be understood, may extend entirely around or substantially around the plate 6.

Mounted on the lower side of the plate 6 I illustrate a latch member 14 shown as formed of sheet metal and mounted on or forming part of a lever 15 pivoted as at 16 for rotation about a vertical pivot and urged by a spring 17 toward latching position. 18 is any suitable retaining member for the lever 15 which may be secured to the bottom of the plate 6. 19 is a downwardly projecting lug on the end of the lever 15 which is adapted to receive any suitable operating element or rod 20 which terminates in any suitable operating handle member diagrammatically shown at 21. The member 21 may be mounted on or adjacent the instrument panel 4 of the vehicle, in a position convenient to the driver's seat.

22 indicates a transversely extending plate mounted on the hood closure 2, for example upon intermediate brackets 23 secured upon the inner turned lower edges or flanges 24 of the hood closure 2. It will be understood, of course, that any suitable securing and supporting means may be employed. I illustrate the member 22 as mounted for longitudinal adjustment and for that purpose I provide adjusting slots 25 through which pass any suitable securing bolts 26 whereby the member 22 is secured upon the upper inner flanges of the brackets 23. The transversely extending member 22 is upwardly offset as at 27, which offset may serve as a reinforcing means and is not in general essential. It is also provided with a circumferential reinforcing flange 28, shown as upwardly extending.

Mounted on the upwardly offset central portion 27 is a combined centering and locking yoke or keeper 29 which may for example be formed of rod stock and which has curved or beveled corners 30. The upper ends of each arm may be screw-threaded as at 31 to receive adjusting

and locking nuts 32. Mounted upon the ends 31 and secured in position by said locking nuts is a spring yoke 33 in which is positioned a coil compression spring 34 through which passes the pin 35, the end of which extends upwardly through the aperture 36 in the upper end of the yoke or guide 33. To the lower end of the pin 35 is secured a plate 37 and a washer 38 which serves as a lower abutment for the spring 34. The plate 37 is slotted as at 39 to permit the passage therethrough of the arms of the yoke 29 and is of sufficient size to abut normally against portions of the upper face of the transversely extending lower plate 6, as shown for example in Fig. 4.

Any suitable pads or cushioning members of rubber or the like, as shown at 40, may be employed for cushioning the contact between the opposed portions of the hood 1 and the hood closure 2.

I provide a secondary or safety latching means which includes a lever or hook 41 with a latching or hook portion proper 42. The hook member is pivoted as at 43 between ears 44 which may be downwardly struck from the upper transverse plate 22. Any suitable means may be employed for urging the hook 42 normally into vertical alignment with the securing lip 12. I illustrate for example a coil spring 45. The hook is provided also with a finger or handle piece 46, preferably formed integrally therewith, the purpose of which will later appear.

It will be realized that whereas I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of my invention are as follows:

Referring to the drawings, I provide a compact unitary structure for carrying a lock or latch which holds the closure 2 in final locked position, an additional latch 41 which permits a limited upward movement of the closure 2, and a spring 34 which, through the pin 35 and the plate 37, tends yieldingly to lift the closure 2 to the upward limit of movement permitted by the hook portion 42 of the latch 41. Normally it need not raise the closure to the full limit of the latch 41, but if the closure 2 happens to be blown open during the movement of the car, the hook 42 positively limits the upward movement of the closure 2.

The main latch 14 cannot be actuated from the exterior of the hood except by the actuation of the operating handle 21 inside the car itself. Assume that the operator wishes to give a filling station attendant access to the engine, he may pull on or otherwise actuate the handle 21, with the result that the latch 14 is withdrawn to released position. The spring 34 then lifts the closure 2 a distance which cannot exceed the full length of the hook 41, 42, but which in practice will be only a fraction of the possible lift. However, this lift is in practice sufficient to permit the operator to insert his fingers under the forward end of the hood closure 2 in order to complete the lifting of the closure.

The member 46 is conveniently located and is conveniently shaped to receive the hand or fingers of the operator so that the operator, by a single unitary upward lift, moves the hook 42

5 to release position and lifts the closure 2 to any desired height. It will be understood that any suitable means may be employed, not herein shown, for holding the closure 2 in upward position when it once has been lifted.

In the operation of the device, the yoke 29 serves the unitary purpose of guiding the closure 2 into proper position in relation to the hood 1. For initial adjustment, the plate 8 may be laterally adjusted and the plate 22 may be longitudinally adjusted. The rounded corners 30 of the yoke 29 serve as centering means for centering the hood 2 in proper position when it is downwardly moved. There is a very slight transverse clearance between the yoke 29 and the inner faces of the aperture 1. There is, however, a substantial longitudinal clearance to permit tilting.

The lower end of the yoke 29 further serves 20 as a keeper to receive the bottom face 14b of the member 14. In practise it can be straight but a slight inclination may be helpful. The inclined faces 14a permit the yoke 29 to override the latch 14 against the action of the spring 17. 25 As soon as the yoke clears the bottom of the latch 14, the spring 17 is effective to move it into the latching position.

Normally the closure 2 is thus firmly locked. There is always, however, a possibility that the 30 operator may not move the closure down quite far enough to obtain a complete locking effect. In this event, the latch hook 42 is effective since the spring 45 keeps it at all times in vertical alignment with that portion of the flange 13 which extends along the locking lip 12 of the plate 6. Thus, even if the hood closure 2 is lifted by the wind caused by movement of the car, it can only be lifted through an arc sufficient to cause the hook 42 to engage the flange 13 and further unintended upward movement of the hood closure 2 is thus prevented.

I claim:

1. In locking means for an automobile hood having hingedly connected members with latch-part mounting members on the respective hood members, one of said mounting members being vertically superposed over the other when the hood is in closed position, a combined centering member and keeper mounted on and vertically adjustable in relation to one of said mounting members, the other mounting member being apertured to receive said keeper in guiding relationship, and a thrust member mounted on and guided by said keeper, and yielding means adapted to urge said thrust member against said opposite latch-part mounting member whereby, when the keeper is released, the thrust member is adapted to lift the upper hinged member, said centering member and keeper including a generally U-shaped loop having two generally parallel stems, said thrust member being slidably mounted on both of said stems and being apertured to permit the passage of said stems therethrough.

2. In locking means for an automobile hood having hingedly connected members with latch-part mounting members on the respective hood members, one of said mounting members being vertically superposed over the other when the hood is in closed position, a combined centering member and keeper mounted on and vertically adjustable in relation to one of said mounting members, the other mounting member being apertured to receive said keeper in guiding relationship, and a thrust member mounted

on and guided by said keeper, and yielding means adapted to urge said thrust member against said opposite latch-part mounting member whereby, when the keeper is released, the thrust member is adapted to lift the upper hinged member, said centering member and keeper including a generally U-shaped loop having two generally parallel stems, said thrust member being slidably mounted on both of said stems and being apertured to permit the passage of said stems therethrough, the yielding means including a coil spring compressed between said thrust member and the latch-part mounting member on which the centering member and keeper is mounted.

3. In locking means for an automobile hood having hingedly connected members with latch-part mounting members on the respective hood members, one of said mounting members being vertically superposed over the other when the hood is in closed position, a combined centering member and keeper mounted on and vertically adjustable in relation to one of said mounting members, the other mounting member being apertured to receive said keeper in guiding relationship, and a thrust member mounted on and guided by said keeper, and yielding means adapted to urge said thrust member against said opposite latch-part mounting member whereby, when the keeper is released, the thrust member is adapted to lift the upper hinged member, said centering member and keeper including a generally U-shaped loop having two generally parallel stems, said thrust member being slidably mounted on both of said stems and being apertured to permit the passage of said stems therethrough, the yielding means including a coil spring compressed between said thrust member and the latch-part mounting member on which the centering member and keeper is mounted, and an abutment member for said spring including a recessed offset portion into which said spring penetrates.

4. In locking means for an automobile hood having hingedly connected members with latch-part mounting members on the respective hood members, one of said mounting members being vertically superposed over the other when the hood is in closed position, a combined centering member and keeper mounted on and vertically adjustable in relation to one of said mounting members, the other mounting member being apertured to receive said keeper in guiding relationship, a thrust member mounted on and guided by said keeper, yielding means adapted to urge said thrust member against said opposite latch-part mounting member whereby, when the keeper is released, the thrust member is adapted to lift the upper hinged member, said centering member and keeper including a generally U-shaped loop having two generally parallel stems, said thrust member being slidably mounted on both of said stems and being apertured to permit the passage of said stems therethrough, the yielding means including a coil spring compressed between said thrust member and the latch-part mounting member on which the centering member and keeper is mounted, an abutment member for said spring including a recessed offset portion into which said spring penetrates, and unitary means for securing the abutment member and the centering member and keeper in relation to the mounting member on which they are mounted.

5. In locking means for an automobile hood 75

having hingedly connected members with latch-part mounting members on the respective hood members, one of said mounting members being vertically superposed over the other when the hood is in closed position, a combined centering member and keeper mounted on and vertically adjustable in relation to one of said mounting members, the other mounting member being apertured to receive said keeper in guiding relationship, a thrust member mounted on and guided by said keeper, and yielding means adapted to urge said thrust member against said opposite latch-part mounting member whereby, when the keeper is released, the thrust member is adapted to lift the upper hinged member, said centering member and keeper including a generally U-shaped loop having two generally parallel stems, said thrust member being slidably mounted on both of said stems and being apertured to permit the passage of said stems therethrough, the yielding means including a coil spring compressed between said thrust member and the latch-part mounting member on which the centering member and keeper is mounted, said coil spring being located between said two stems.

6. In a locking means for an automobile hood including hingedly connected hood members and having a latch on one such member and a keeper on the other, and a pair of latch-part mounting members, one mounted on one of said hinged members and the other on the other, a combined centering member and keeper mounted on one of the members and having a bolt receiving portion, the other of said members having an aperture to receive said keeper when the hood members are in closed position, the latch being mounted on the apertured mounting member and adjacent the aperture and including a portion adapted for latching engagement with the keeper, the combined centering member and keeper being mounted for ready vertical adjustment, a thrust member including a disk-like member mounted on and guided by said keeper, and yielding means adapted to urge said thrust member against the opposite mounting member whereby, when the keeper is released, the thrust member, through its contact with the mounting member, is adapted to lift the upper hinged member, said yielding means including a spring confining said thrust member between the mounting members and causing said thrust member to move toward the bolt receiving portion of the keeper to a point proximate thereto when the hinged member is released.

7. In a locking means for an automobile hood including hingedly connected hood members and having a latch on one such member and a keeper on the other, and a pair of latch-part mounting members, one mounted on one of said hinged members and the other on the other, a combined centering member and keeper mounted on one of the members and having a bolt receiving portion, the other of said members having an aperture to receive said keeper when the hood members are in closed position, the latch being mounted on the apertured mounting member and adjacent the aperture and including a portion adapted for latching engagement with the keeper, the combined centering member and keeper being mounted for ready vertical adjustment, a thrust member including a disk-like member mounted on and guided by said keeper, and yielding means adapted to urge said thrust member against the opposite mounting member, whereby, when the

keeper is released, the thrust member, through its contact with the mounting member, is adapted to lift the upper hinged member, said yielding means including a spring confining said thrust member between the mounting members, and causing said thrust member to move toward the bolt receiving portion of the keeper to a point proximate thereto when the hinged member is released, said centering member and keeper including a stem secured to said mounting member, said thrust member being slidably mounted upon and guided by said stem and being apertured to permit the passage of the stem therethrough.

8. In a locking means for an automobile hood including hingedly connected hood members and having a latch on one such member and a keeper on the other, and a pair of latch-part mounting members, one mounted on one of said hinged members and the other on the other, a combined centering member and keeper mounted on one of the members, and having a bolt receiving portion, the other of said members having an aperture to receive said keeper when the hood members are in closed position, the latch being mounted on the apertured mounting member and adjacent the aperture and including a portion adapted for latching engagement with the keeper, the combined centering member and keeper being mounted for ready vertical adjustment, a thrust member including a disk-like member mounted on and guided by said keeper, and yielding means adapted to urge said thrust member against the opposite mounting member whereby, when the keeper is released, the thrust member, through its contact with the mounting member, is adapted to lift the upper hinged member, said yielding means including a spring confining said thrust member between the

mounting members and causing said thrust member to move toward the bolt receiving portion of the keeper to a point proximate thereto when the hinged member is released, said centering member and keeper including a stem secured to said mounting member, said thrust member being slidably mounted upon said stem and constituting a generally horizontal member having a generally flat portion opposed to the apertured mounting member upon which the latch is mounted.

9. In a locking means for an automobile hood including hingedly connected hood members and having a latch on one such member and a keeper on the other, and a pair of latch-part mounting members, one mounted on one of said hinged members and the other on the other, said mounting members being vertically superposed when the hood is closed and being spaced vertically apart, a combined centering member and keeper mounted on one of the mounting members and having a bolt receiving portion, the other of said members having an aperture to receive said keeper when the hood members are in closed position, the latch being mounted on the apertured mounting member and adjacent the aperture and including a portion adapted for latching engagement with the keeper, a thrust member mounted on and guided by said keeper, and yielding means adapted to urge said thrust member against the opposite mounting member, whereby, when the keeper is released, the thrust member, through its contact with the mounting member, is adapted to lift the upper hinged member, said yielding means including a spring extending between said mounting members when the hood is closed.

ROWLAND HILL.
